GARMENT FINISHING PRESS

Harry D. Forse, Anderson, Ind.

Application March 9, 1945, Serial No. 581,797

4 Claims. (Cl. 38—41)

1

This invention relates to improvements in presses and more particularly to a garment finishing press for laundries and dry-cleaning establishments.

It is an object of this invention to provide a press of this character with a frame constructed of sheet metal upon which the moving parts are mounted within and upon a sheet metal hood. The entire press presents a pleasing symmetrical stream-lined outline to the eye.

It is a further object of this invention to support a buck upon the frame to cooperate with a head carried upon the underside of the front of the hood for manually engaging and disengaging the head with the buck, in which the pivoted hood takes the place of the conventional rocker arm supporting the head. It is a further object of this invention to provide a device of the character just described with means for imparting additional pressure to the head after it has been brought into pressing relation with the buck and the additional provision of the application of fluid pressure to supplement the manual pressure at the end of the pressing engagement.

This improved press does not only present a pleasing appearance to the eye but by enclosing all of the moving parts within the frame and hood adds to the safety of the operator as the hood prevents any member of the operator's body or clothing from becoming entangled in the moving parts.

This improved press is of particular advantage to the dry-cleaning establishments because in pressing the majority of articles which have been dry-cleaned it is only necessary to apply momentary pressure which can be readily and easily attained by the manual operation of this press. The press has the additional feature where it is found necessary in pressing certain materials to exert an additional power to the pressing head to complete the pressing and this improved press provides means for applying this additional power during the manual operation as well as providing a fluid pressure means which may be readily actuated by the operator at the end of the pressing stroke. Another advantage is the provision of means whereby after the application of fluid pressure to complete the pressing operation the press will be locked in that position until manually released by the operator.

With these and other objects in view reference is made to the accompanying sheets of drawings illustrating a form of this invention, with the understanding that detail changes may be made without departing from the scope thereof.

2

In the drawings:

Figure 1 is a view in side elevation of this improved press showing the position assumed by the parts during the pressing operation.

Figure 1a is a sectional view of the improved press taken on line 1a—1a of Figure 1.

Figure 2 is a view in front elevation of Figure 1.

Figure 3 is an enlarged detail view in central vertical section of the head and upper portion of the frame showing the position assumed by the moving parts in full lines at the close of the pressing operation and in dotted lines in the position assumed at the beginning of the opening of the press.

Figure 4 is a view in section taken on the line 4—4 of Figure 3 looking in the direction of the arrows.

Figure 5 is a view similar to Figure 3 illustrating the position of the moving parts assumed when the press is in the open position.

The embodiment of this invention as illustrated includes a frame 1 and hood 2 formed of sheet metal. As shown in Figures 1 and 2 the opposite sides of the frame are spaced apart in parallel relationship joined together at the front by a cylindrical portion tangential to the sides. The front and sides of the frame are cut away to form a horizontal shelf extending about two-thirds of the way to the rear of the frame. The sides of the frame extend symmetrically above the shelf to form a support for a pivot shaft 3 upon which the hood 2 is mounted. This projection slopes rearwardly and upwardly from the shelf and this is curved about the pivotal support and is carried therebeyond on an arc of a circle tangential to the rear vertical ends of the sides. The rear vertical ends of the sides and the projection above the shelf are provided with right angular inturned flanges 4 which give the frame rigidity. The sides of the frame at the rear are connected to each other by a plate 5 attached to the inturned flanges which is terminated a sufficient distance below the pivotal point of the hood to allow the hood to be rotated and the rear portion received between the sides of the frame.

The hood 2 is also formed of sheet metal having spaced apart parallel vertical side members which are curved at the front toward each other and extend into a flat front wall. The side walls at the bottom extend inwardly a short distance at right angles to the front and are then curved downwardly. The side walls at the top are curved upwardly from the flat front and then downwardly to join the lower walls. The hood at the

bottom is open and is closed at the top by a continuous curved plate connecting the edges of the curved side walls. By this construction the working parts of the members may be enclosed within the hood and frame. The hood 2 is mounted to rotate about a horizontal pivot shaft 3 passing through the side walls and engaging supports 6 provided in the upper extremities of the side walls of the frame covered by the in-turned flanges 4.

A rectangular table 7 preferably of enameled sheet metal ware is supported upon the horizontal shelf formed in the side walls and extending upwardly upon the angular portion and terminating in front of the frame in a curved or ribbed edge. A buck 8 supported upon a standard 9 is mounted upon the top of the table 7 and this portion of the table may be reinforced by an angle iron 10 extending transversely across the shelf and secured at its ends to the side walls of the frame. The cooperating pressing head 11 is carried on a plate 12 extending across the bottom of the hood 2 at the front and secured to the walls thereof. The hood 2 is normally held in its open position, shown in Figure 5, by coiled springs 13 anchored at one end to a rod 14 extending transversely of the hood and secured to the opposite interior surfaces of the side walls at a point adjacent the meeting of the curved edges at the rear and at the other end to a stud 15 extending inwardly from each side wall at a point below the pivotal shaft 3 so arranged that the springs are placed under tension when the press is closed. The flanges 4 of the frame are cut away to allow the spring to move with the hood from open to closed position.

A mechanism is provided for the manual closing of the hood to bring the head and buck into pressing relationship. This mechanism includes a pair of parallel handles 16 passing through vertical slots 17 in the front of the hood 2 joined together by a hand grip 18. These spaced apart handles are preferably formed of right angular extensions from a connecting plate 19 attached to a rearwardly extending central bracket 20, the upper end 21 of which is mounted upon a horizontal pivot 22. This horizontal pivot 22 is preferably mounted between two similar brackets 23 extending on each side of the center of an angle iron or I-beam 24 secured to the opposite sides of the hood 2. The horizontal bracket 20 is provided with a depending rearwardly extending portion 25, the upper surface of which is formed on a re-entrant curve 26 which includes a cam track 27 and the rear surface thereof includes a cam track 27¹. A cam roller 28 adapted to travel over the cam tracks 27 and 27¹ is mounted between the upper ends of two bars 29 receiving between them this portion 25 of the horizontal bracket 20, which bars 29 are mounted upon the hood pivot 3 and extend therebelow to terminate below the table 7 with their lower ends joined by a pivoted spacer 30. An adjusting rod 31 is threaded through the spacer 30 at one end and extends through the front of the frame at the other end and is rotatably mounted in the front of the frame between disks 32 secured to the shaft on the inner and outer sides of the frame, the outer disk being provided with a knurled knob 33 by which the rod 31 may be rotated to alter the relation of the roller cam carrying bars about the pivot of the hood.

The cam roller supporting bars 29 are so positioned by the adjusting rod 31 that when the hood is in the open position as shown in Figure 5

the underside of the portion 21 of the handle bracket 20 which surrounds the pivot 22 will be engaged by the upper side of the cam roller 28. When the operator grasps the hand grip 18 and pulls forwardly and downwardly upon it the hood 2 is rotated counter clockwise and the cam roller 28 travels over the re-entrant curved portion of the handle bracket thereby rotating the handle bracket assembly clockwise on its pivot 22. Thus in arriving at a position wherein the buck 8 and head 11 are in confronting position, as shown in solid lines in Figure 3, and the handle bracket assembly is in substantially its dotted line position. In other words, the handles 16 are elevated and the cam track 27¹ engages, or is in position to engage, the cam roller 28. With the parts so positioned counter clockwise rotation of the handle bracket assembly on its pivot 22 causes the cam track 27¹ to be operably advanced on the roller 28 whereby additional pressure is imposed on the head 11. It is to be noted that when the cam track 27¹ engages the roller 28, a latching means is provided for locking the press against opening movement. Thus the cam track 27¹ in conjunction with the cam roller 28 is a dual purpose arrangement. The cam track 27 over which the roller travels in closing the head is formed on the radius of a circle. The relationship of the center of the cam track radius with the axes of the hood pivot 3 and handle pivot 22 is such that as the cam roller travels over the cam track from the position shown in Figure 5 in closing the head, it will force the handle upwardly to the position shown in dotted lines in Figure 3. Therefore, when the cam roller rolls over the end of the cam track 27, the continued pressure on the handle toward the position shown in full lines in Figure 3 imparts additional pressure upon the head against the buck. As shown in Figure 3, the lower rearwardly extending portion 25 of the handle bracket is provided with a rearwardly extending lug 34 at the base of the cam track 27¹. The lug 34 provides an abutment through which an adjusting screw 35 may be threaded to limit the upward movement of the portion 25.

At times it is desired to exert more than manual pressure upon the head. As most dry-cleaning establishments are equipped with steam under pressure this additional power may be imparted to the downward movement of the handle by a power cylinder 36 secured to the upper closure of the hood 2 above the handle and including a piston and piston rod 37 extending through the cylinder head and adapted to engage the handle bracket between the handle pivot 22 and the bifurcated handles 16. A control valve 38 is mounted on one of the handles 16 connected at one end through a pipe 39 to a source of fluid pressure, steam or air, whichever is most convenient, and at the other end through pipe 40 to the interior of the power cylinder 36. The control valve may be of any desired commercial structure whereby the depression of the upwardly biased valve stem 41 will connect the power cylinder to the source of fluid pressure and in its normal biased position connect the power cylinder to an exhaust 42. In order that the operator may readily apply this additional pressure, a valve operating arm 43 is pivotally mounted upon the handle supporting the valve which handle is provided with an operating button 44 adjacent the hand grip 18 so that the operator by depressing this button will operate the power cylinder to exert the additional pressure desired. Upon re-

leasing the button, the operating arm 43 will be returned to its normal position by the upwardly biased valve stem 41 in the valve, or by an additional spring 43a secured to the handle, to cut off the power cylinder 36 from the source of fluid pressure and exhaust the cylinder to the atmosphere. In dry-cleaning establishments it is often desirable to lock the press after the additional pressure has been applied to allow the operator to service another press. This can be accomplished by the provision of a latch 45 adapted to engage the operating button 44 when it is depressed and hold it in its depressed position until the operator releases it.

It is also preferable to provide a spring 46 between the handle 16 and head carrying plate 12 adjacent the front of the hood 2 to prevent too rapid travel of portion 25 of the handle bracket in relation to the cam roller 28 when the latch is released and the parts moved from the full line position to the dotted line position shown in Figure 3 and also to cushion any impact between the curved edge 26 and the cam roller 28 at the end of the return movement.

It is to be particularly noted that the cam track 27¹ at the rear of the portion 25 between the cam track 27 and the lug 34 forms a bearing surface which engages the roller 28 to impart the final downward movement of the head as shown in Figure 3 and also provides a latch for locking the head against return movement. Thus the downward movement of the head from the position shown in Figure 5 to the position shown in Figure 3 will cause the cam track 27 to pass under the roller 28 to elevate the handles 16 and then the portion 27 to engage the roller under the action of the biasing spring 46 to lock the head in lowered position. The biasing force of the spring 46 on the handles 16 is sufficient to maintain the latch in locked position without manual assistance. The latch may be released only by rotating the handle bracket assembly in a clockwise direction.

What I claim is:

1. In a garment press a frame, a buck supported upon the frame, a head, a hood mounting the head at its front end and pivoted intermediate its length to the frame, an operating arm pivotally mounted within the hood above the frame pivot, a cam roller mounted between the ends of a pair of spaced apart bars mounted upon the frame pivot and anchored to the frame therebelow at the other end, said operating arm in-

cluding a pair of operating handles extending through the hood at the front, said operating arm having a depending rearwardly extending portion below the arm pivot providing a cam track to engage the under side of the cam roller whereby movement of the exterior of the handles imparts movement to the hood about its pivot to bring the head into and out of pressing relation with the buck.
